[57] CLAIM

The ornamental design for a transparent shield for the front end of an automobile, as shown and described.

DESCRIPTION

FIG. 1 is a perspective view of a transparent shield for the front end of an automobile showing my new design;
FIG. 2 is a front elevational view thereof;
FIG. 3 is a rear elevational view thereof;
FIG. 4 is a top plan view thereof; and
FIG. 5 is a right side elevational view thereof, the other side being a mirror image.

FIG. 2.

FIG. 3

FIG. 4.

FIG. 5.
